CLAIM

The ornamental design for a coffee machine as shown and described.

DESCRIPTION

FIG. 1 is a perspective view of a coffee machine of the present invention;

FIG. 2 is front view of the invention shown in FIG. 1;

FIG. 3 is rear view of the invention shown in FIG. 1;

FIG. 4 is a left-side view of the invention shown in FIG. 1;

FIG. 5 is a right-side view of the invention shown in FIG. 1;

FIG. 6 is a top view of the invention shown in FIG. 1; and,

FIG. 7 is a bottom view of the invention shown in FIG. 1. The invention is a coffee machine, as shown in the FIGS. 1 through 7. Contour lines are included in the various views of FIGS. 1 through 7 to depict surface curvature, flatness and/or other shapes.
